UNITED STATES PATENT OFFICE.

EDWARD J. POPE AND CHARLES E. POPE, OF EAU CLAIRE, WISCONSIN.

PAPER-REEL.

SPECIFICATION forming part of Letters Patent No. 411,608, dated September 24, 1889.

Application filed September 3, 1888. Serial No. 284,413. (No model.)

To all whom it may concern:

Be it known that we, EDWARD J. POPE and CHARLES E. POPE, of Eau Claire, in the county of Eau Claire, and in the State of Wisconsin, 5 have invented certain new and useful Improvements in Paper-Reels; and we do hereby declare that the following is a full, clear, and exact description thereof.

Our invention relates to reels for taking the 10 paper from the calender-rolls in paper-mills, and will be fully described hereinafter.

In the drawings, Figure 1 is an elevation of one side of our improved reel-frame. Fig. 2 is an elevation of the opposite side. Fig. 3 15 is a plan view. Fig. 4 is a detail section; Fig. 5, a longitudinal section of one of the paper-reels, and Fig. 6 a detail cross-section of the same. Figs. 7, 8, and 9 show modifications.

A is the base of our machine, and B is the 20 reel-frame, the shaft B' of which has bearings at a a' on the stand. The arms C C of the reel-frame carry the reels or rollers D, the shafts b of which have suitable bearings in the ends of said arms.

25 E is a cog-wheel that is secured at one end of the reel-frame, and this is driven by a pinion c on the shaft d by the hand-wheel or crank e, to turn the wheel after each reel has received its complement of paper.

30 Shaft h' carries pulley j, which latter is connected by a belt K with suitable driving-power. A sprocket-wheel F is fastened on the inner end of shaft h', and this wheel carries an endless chain h², which stands in position to receive each of the pinions G, that are fixed each 35 to an end of one of the reels D, as it is presented to it from below and comes into engagement with pinion G just as the latter comes out of engagement with pinion N', and the endless chain comes out of engagement with each pinion G just as its successor gets in position 40 for work.

45 Pulley N and its shaft N² are driven by any suitable power to drive pinion N', which latter is always in position to receive pinions G, successively, as they are presented from below.

50 Each of the reels D is formed with a longitudinal channel B², to receive a rock-shaft B³, on which is fixed a series of slightly-curved teeth B⁴. These rock-shafts are each suitably

journalled on the reel, and one end is shaped to receive an end of a flat spring B⁵, which serves as a yielding lock to prevent it from turning except at the proper time. 55

One end of each shaft B³ comes outside of the head of its reel, and carries a dog B⁶, and an arm B⁷ projects out from the adjacent bearing of each reel in the path of this dog, so that when the empty reel begins to turn in 60 the direction indicated by the arrow in Fig. 1 the dog will be struck by the arm and the teeth will be forced through the paper and over in position to clamp it down on the reel.

The operation of our device is as follows: 65 While a reel is being filled the parts are in position, as shown in Fig. 2. When a reel has been filled and it is necessary to put an empty one in place of the one filled, the reel-frame is turned by means of the crank or 70 hand-wheel e, and the pinion of the filled reel is lifted out of engagement with pinion N' and into engagement with endless chain h². The reel now gets its motion from the chain h² and continues to revolve as it is lifted by 75 the revolution of the reel-frame until the empty reel on the next lower arm C comes up to the paper between the last-filled reel and a depressing-roll T. The arm B⁷ now strikes the dog as the empty reel commences to revolve and throws the teeth over, through, and onto the paper, thus cutting and clamping it as the reel revolves, and thus a filled reel is 80 replaced by an empty one without any cessation in the winding of the paper, and no paper is lost by the change from one reel to the other. 85

The upper loop of belt h² passes over a smooth pulley h³, the shaft of which has its bearing on a standard L, that projects up 90 from the standard A, and this belt has slack enough to allow of its yielding to permit the pinions G of the reels D to describe their circle in the revolution of the reel-frame.

In Figs. 7, 8, and 9 is shown a modification 95 of our invention, wherein for chain h² is substituted a pinion M, the shaft M' of which is journalled in one end of an arm M², the outer end of which is fitted loosely on the shaft B' of the reel-frame. The outer end of shaft M' 100 is also carried by an end of an arm M³, the other end of which arm is loosely fitted on a

short shaft E', one end of which is stepped in an end of shaft B', while its other has its bearing in a stand H. The shaft M' also carries a pinion M⁴, and this pinion is connected by an intermediate gear-wheel H' with a pinion E⁴ on shaft E', which shaft carries a pulley E², that is connected by a belt E³ with a driving-power. A sliding catch m is fitted in arm M², and this catch is held over the path of the reel-frame arms when the arm M² is in a nearly horizontal position by an inclined arm n, that projects up from the stand A, which arm wedges against the inclined head of the catch m, and when the arm M² is being lifted by one of the arms of the reel-frame the friction between the catch and reel-frame arm serves to hold the catch over the said reel-frame arm against the tension of a spring p, that is fixed at one end to the arm M², while its other engages the catch-head with a tendency to draw outwardly on the catch; but after the arm M² has been raised to an angle of about forty-five degrees the weight of it becomes insufficient to overcome the tension of the spring, and therefore the catch is withdrawn by the spring and the arm M² drops to the support P, in position to bring the pinion M in position to mesh with the next filled reel that rises, so that each newly-filled reel is turned until the succeeding empty one gets in position for work.

In the modification just described the pinion F is removed from its shaft h' and the described pinion N' is substituted therefor, performing the same office in its new location that it did when mounted on shaft N² in Fig. 3.

Having thus fully described our invention, what we claim as new, and desire to secure by Letters Patent, is—

1. In a paper-reeling device, the combination, with the frame and reels and their pinions and a fixed power-driven pinion for successively revolving said reels, of a suitably-driven chain arranged to overhang the path of each newly-filled reel while it is rising to give place to an empty reel and to engage the pinion of said filled reel and revolve it until the paper is taken by the next lower reel, substantially as described. 40

2. The combination, with a paper-reel frame and reels carried thereby, of pinions fixed on the shafts of said reels, a suitably-driven stationary pinion for revolving each reel in succession when the reel-frame is at rest, and other driving-connections adapted to engage the pinion of each newly-filled reel as it is lifted by the turning of the reel-frame to give place to an empty reel, substantially as described. 50

3. The combination, with a paper-reel frame, of a reel, a rock-shaft, and clamping and cutting teeth carried thereby, a dog secured to one end of the rock-shaft, and a tripping-arm carried by the reel-frame arm and adapted by engagement with said dog to revolve the rock-shaft and cause the teeth to clamp and cut the paper as the reel revolves under it, substantially as described. 60

In testimony that we claim the foregoing we have hereunto set our hands, at Eau Claire, 70 in the county of Eau Claire and State of Wisconsin, in the presence of two witnesses.

EDWARD J. POPE.
CHARLES E. POPE.
